FOLDING TABLE

William C. Rastetter, Fort Wayne, Ind.

Application April 13, 1936, Serial No. 73,990

8 Claims. (Cl. 311—99)

This invention relates to improvements in folding tables wherein the legs are pivotally connected within a table top and associated with mechanism for locking the several legs when in extended position and latching the legs frictionally in their folded positions.

An object of the invention is the provision of a locking mechanism for each of the legs by which the legs are sustained in extended position and in which the locking mechanism for each leg is moved from locking position upon folding of the leg adjacent thereto.

Other objects and advantages of the invention appear in the following description.

An illustrative embodiment of the invention is shown in the accompanying drawings, in which:

Fig. 1 is a bottom plan view of a table made in conformity with the invention, the legs being shown in folded position;

Fig. 2 is a top plan view of one of the table legs including its reinforce;

Fig. 3 is a fragmentary side elevation projected from Fig. 2;

Fig. 4 is a fragmentary cross-sectional view showing the connection of one of the legs with the table top, the locking mechanism therefor and an adjacent leg cooperatively associated with said mechanism;

Fig. 5 is a similar view showing partially a projection from Fig. 4 in a plane at right angles thereto; and

Fig. 6 is another fragmentary cross-sectional view similar to Fig. 4 but showing one of the legs in latched position and unlocking another leg to permit folding thereof.

The illustrative embodiment of the invention is constituted of a rectangular table top 1 provided with marginal pendant frame members 2 and preferably having an inner supporting frame 3 disposed at the juncture of the top and its frame members.

In each corner of the table top secured to the corresponding frame members is located a U-shaped bracket 4 formed preferably of sheet metal, the bracket being secured to said frame members by means of screws 5, and also to said inner supporting frame by a screw 6 which extends through a perforated lug 7 that is cut out of the adjacent inner wall of the bracket and bent at right angles thereto so that an opening 8 (Fig. 5) is left in said wall, hereinafter referred to.

Legs 9, 10, 11 and 12 are pivotally secured respectively to the corresponding brackets 4 by means of a lag screw 13 that passes through the

walls of the corresponding bracket 4 and the leg. Preferably, the upper end of each leg has thereon a reinforce or metal facing 14 that is secured thereto by means of screws 15, through which the corresponding lag-screw 13 extends, there being an opening 16 made through the leg and the facing walls for the accommodation of the lag-screw. The lag-screw forms a pintle upon which the corresponding leg turns in its bracket 4.

In the upper part of each leg is made a bore 17 that extends through the inner wall 18 of the reinforce 14 and terminates at the outer wall 19 of the reinforce where the bore is closed. In the bore 17 of each leg is disposed a lock-bolt 20 and an expansion spring 21 that bears against the outer wall 19 of the reinforce 14 and one end of the bolt. The opposite end of the bolt 20 is rounded off to form a tapering nose 22 that protrudes through the inner wall 18 of the facing on the leg and has locking relation with the corresponding bracket 4 when the leg is moved into its fully extended position, there being made in the inner wall of the bracket an opening 23 for reception of the outer end portion of the bolt. The opening 23 is preferably of smaller bore than the diameter of the bolt so that when in locking position the bolt fits tightly therein and prevents wobbling of the leg upon its pintle. When the leg is moved into folded position the nose of the bolt protrudes to a limited extent into the lug opening 8 in the bracket and thereby the leg is yieldingly held in folded position. The lug opening 8 is located in the bracket a sufficient distance from the pintle as to lie partially out of the path of the bolt when the leg is folded and thus is prevented locking engagement of the bolt in the lug opening.

In juxtaposition with each bracket 4 is secured a spring 24 preferably consisting of a metallic strip rigidly secured at one end to the adjacent face of said bracket and shaped to have an offset 25 and a backturned movable free end 26 that overlaps the opening 23 in the bracket 4 and bears against the nose of the corresponding bolt when the leg is extended and the bolt is in locking position. Thus, when pressure is applied to the free end of the spring the bolt is pressed back into the bore of the leg in opposition to the action of the expansion spring 21 a sufficient distance to permit folding movement of the leg upon its pintle.

The free end of each leg has thereon a knob 27 that when the leg is folded contacts with and exerts pressure against the free end 26 of the spring 24 that is associated with an adjacent leg 55

causing the lock-bolt to be moved from its locking engagement to permit folding of said adjacent leg. The offset 25 on the spring 24 acts as a stop and rest for the free end of the adjacent 5 folded leg, and coincidentally the free end of said spring has latching relation with the folded leg engaged thereby.

In operation, the legs are moved from folded position in successive order to their fully extended 10 position whereupon they become automatically locked by engagement of their respective bolts in the corresponding brackets. In folding the table, pressure is manually applied against one of the springs 24 to move the corresponding bolt back- 15 wardly and thus permit folding of the corresponding leg. When the leg thus unlocked is moved to folded position, the knob 27 on its free end contacts and bears against the spring 24 of the adjacent leg thus automatically unlocking the 20 adjacent leg and permitting folding thereof. Said adjacent leg upon being folded similarly causes unlocking of the next succeeding leg, which succeeding leg, upon being folded, similarly unlocks the next leg, and so forth, until all of the legs 25 shall have been unlocked and folded. In this manner upon manually unlocking and folding of one leg, each of the other legs are automatically unlocked, one after another in successive order upon folding of the corresponding preceding legs. 30 Thus, upon folding of each leg an adjacent leg is unlocked and itself becomes latched in folded position by the free end 26 of the corresponding spring 24, which action permits folding of the unlocked legs in successive order.

35 What I claim is:—

1. A folding table having a rectangular top provided with pendant marginal frame members, a bracket secured within each corner of said top, each bracket having an inner wall provided with a lock opening, a leg secured upon a pintle in each 40 of said brackets, each leg having in its upper end portion a spring-pressed lock-bolt adapted to have locking engagement with the corresponding bracket by projecting into the lock opening therein when said leg is moved into its fully extended position, and a spring secured at one end in juxtaposition to each bracket and having a movable free end that overlaps the lock opening and has operative relation with the lock-bolt in 45 said leg, the free end of each leg having operative relation with the spring that is associated with the leg adjacent thereto so that when the one leg is moved to folded position the spring engaged by the folded leg causes the corresponding bolt to move from locking position to thereby permit 50 folding of said adjacent leg.

2. A folding table having a rectangular top provided with pendant marginal frame members, a bracket within each corner of said top, each bracket having an inner wall provided with a lock opening, a leg secured upon a pintle in each of 55 said brackets, said leg having in its upper end portion a spring-pressed lock-bolt adapted to have locking engagement with the corresponding bracket by projecting into the lock opening therein when said leg is moved into its fully extended position, and a spring secured at one end in juxtaposition to each bracket and having a movable free end that overlaps the corresponding lock opening and actuates the lock-bolt in said leg when pressure is applied to said spring.

3. A folding table, said table having a top, brackets secured to said top, each bracket having a lock opening, a leg secured upon a pintle in

each of said brackets, said legs each having a spring-pressed lock-bolt adapted to have locking engagement with the corresponding bracket by projecting into the lock opening therein when the corresponding leg is moved into its fully extended position, and a spring secured at one end in juxtaposition to each bracket provided with a movable free end and an offset, said spring having engagement with the lock-bolt in the corresponding leg and with the free end of an adjacent folding leg when the last-mentioned leg is moved to folded position, thereby to move said lock-bolt out of locking engagement. 5

4. A folding table, said table having a top, brackets secured to said top, each bracket having a lock opening, a leg secured upon a pintle in each of said brackets, said legs each having a spring-pressed lock-bolt adapted to have locking engagement with the corresponding bracket by projecting into the lock opening therein when 10 the corresponding leg is moved into its fully extended position, and a spring secured at one end in juxtaposition to each bracket provided with a movable free end, said spring being operatively associated with the lock-bolt in the corresponding leg and with the free end of an adjacent leg 15 when the last-mentioned leg is moved to folded position thereby to move said lock-bolt out of locking engagement. 20

5. A folding table, said table having a top and 30 legs pivoted on said top to have folding movement relative thereto, each leg having means for locking it in extended position, and a member disposed in juxtaposition with the pivoted end of each leg engageable by an adjacent leg when 35 the latter leg is folded for moving said locking means out of locking position whereby the leg thus unlocked may be folded.

6. A folding table, said table having a top and 40 legs pivoted thereon provided each with means to lock same in extended position, and a member operatively related with the lock means of each leg having an offset that functions as a stop to limit folding movement of an adjacent leg and also a free end to unlock the corresponding leg 45 when said adjacent leg is folded.

7. A folding table having a rectangular top provided with pendant marginal frame members, a bracket within each corner of said top, the inner wall of each bracket having a lock opening, a leg 50 secured upon a pintle in each of said brackets, said leg having in its upper end portion a spring-pressed lock-bolt adapted to have locking engagement with the corresponding bracket by projecting into the lock opening therein when said leg is moved to its fully extended position, and a spring secured at one end in juxtaposition to each bracket provided with a movable free end, said 55 spring having engagement with the lock-bolt in the corresponding leg and with the free end of an adjacent folding leg when the last mentioned leg is moved to folded position thereby to move said lock-bolt out of locking engagement.

8. A folding table having a top and legs pivoted thereon provided each with means to lock same 60 in extended position, and a member located adjacent the pivoted end of each leg having operative relation with the lock member thereof and also with the free end of the adjacent leg when 65 said adjacent leg is folded, whereby when each leg is folded the next succeeding leg is unlocked 70 to permit folding thereof.
